UNITED STATES PATENT OFFICE.

WILLIAM P. DUN LANY, OF MAYWOOD, ILLINOIS, ASSIGNOR TO AMERICAN CAN COMPANY, A CORPORATION OF NEW JERSEY.

CHANGE-MAKING MACHINE.

1,231,578.

Specification of Letters Patent. Patented July 3, 1917.

Application filed June 11, 1914. Serial No. 844,397.

To all whom it may concern:

Be it known that I, WILLIAM P. DUN LANY, a citizen of the United States, residing in Maywood, in the county of Cook and 5 State of Illinois, have invented a new and useful Improvement in Change-Making Machines, of which the following is a specification.

The invention has special relation to a 10 change-carrier separable from the rest of the machine, and adapted, when in place, to deliver coins to the ejecting mechanism; also to improved means for locking the coin-ejecting mechanism when insufficient coins 15 are present in the coin reservoirs; and the invention consists in the parts and combinations thereof hereinafter set forth and claimed.

In order to make the invention more 20 clearly understood I have shown in the accompanying drawings means for carrying the same into practical effect without limiting my improvements, in their useful applications, to the practical construction 25 which, for the purpose of example, I have illustrated. In the said drawings:—

Figure 1 is a perspective view of a coin change-making machine embodying the invention.

Fig. 2 is a vertical longitudinal section of 30 the same taken through the middle of the machine.

Fig. 3 is a perspective view of one of the coin-ejecting slides.

Fig. 4 is a perspective view of one of the 35 slide locking levers.

Fig. 5 is a sectional view of a portion of 40 the upper part of the machine showing one of the slides as actuated by its finger lever for the ejection of a coin.

Fig. 6 is a plan view on a larger scale of 45 a portion of the top plate, showing one of the slides in position therein.

Fig. 7 is a vertical longitudinal section of 50 one of the slides and its locking lever, with contiguous parts.

Fig. 8 is a perspective view of the change-carrier detached.

Fig. 9 is a perspective view of the penny 55 changing attachment, shown as separated from the rest of the machine for a better showing of the same.

Fig. 10 is a vertical sectional view near one side of the upper part of the machine,

showing in elevation one of the devices for 55 removably holding in place the coin carrier.

Referring to the drawings, 1 is a casing or shell, preferably of sheet metal, adapted to inclose the greater part of the mechanism, 2 is a frame within the casing, the back- 60 wardly and downwardly inclined top plate 2¹ of which is formed with apertures 3 of various sizes through which different denominations of coins are adapted to pass downward into a chute 4, which is arranged 65 to deliver the coins to a tiltable shelf 4¹ at the front of the machine. This shelf is inclosed by a forwardly extending part 6 of the casing 1 and is movably supported by a spring 7. It may be tilted down by means 70 of a handle 8, as shown in Fig. 2, to deliver into the hand of the operator any change-making collection of coins. The shelf 4¹ may be held depressed and open against the pressure of the spring 7 by means of a cam 75 9 pivoted to the casing 6 at 6¹ and having an operating handle extending out through a slot 11.

12 is a back frame plate arranged at about right angles to the top plate of the frame 2 80 and extending upward and backward therefrom at a point distance from the front of the machine. It is attached to said top plate and braced by plates or brackets 13. The back part of the casing 1 extends over and 85 incloses the margin of the plate 12 by a flange 14. 15 is a removable change-carrier (Fig. 8) adapted to be separated from the rest of the machine and put in a place of safety when the machine is not in use. It 90 comprises a back plate 16 adapted to fit against the front of the fixed plate 12, a bottom shelf plate 17 perforated at 18 for the passage of coins, and semi-tubular coin reservoirs 5, 10, 25 and 50 of different sizes 95 to fit the different coins used in making change; as shown, the reservoirs, from left to right in Fig. 8, are shaped respectively for nickels, dimes, half-dollars, dimes and quarters. The bottom-most coin in each of 100 the reservoirs is to have its bottom surface in contact with, or, in substantially the same plane with, the top surface of the plate 2, just at the rear of the opening 3, and for this purpose and to removably support the 105 stacks of coin in the reservoirs, each reservoir is formed with a pair of hook-like supports 19 the top surfaces of which are flush

with the top of the plate 2, the latter being formed with depressions or openings 21 (Fig. 6) down into which the supports 19 may extend when the carrier 15 is in place. The rear of the plate 16 is provided with tongues 22 adapted to fit in slots 23 formed in the fixed back plate 12. At each side the carrier plate 16 is provided with thumb rests 24 and finger levers 26, the latter being pivoted to the carrier 15 at 27, controlled by springs 28 and formed at their rear ends with catches 29 adapted to enter slots 30 in the fixed plate 12 and engage a shoulder thereof to hold the carrier removably but firmly in place.

31 is an ejecting slide, one of which is provided for each coin reservoir. The slide is provided (Figs. 3 and 6) with downwardly extending lugs 32 which fit in longitudinal slots 33 formed in the plate 2, whereby the slides are guided in a forward and backward reciprocation. The plate 2 may be recessed so as to thus guide the slide, as shown at 34. The slide is cut out at 35 to form an opening 25 to receive the lowest coin of the stack and permit it to slide forward, from under the other coins, on the top surfaces of the plate 2 and supports 19. This forward sliding of the coin is caused by the ejecting slide 31, the rear part 36 of the opening 35 acting as a pusher. The slide is normally held retracted by a spring 37.

Each ejecting slide is engaged, in a recess or slot 38, by the rear, upper, forwardly propelling end 39 of a lever 40, these levers being pivotally mounted on a transverse shaft or rod 41, and thereon spaced apart by a partition 42 in which are formed slots for the levers to work in. They are also guided in vertical planes by their rear ends by a curved fixed plate 43 slotted at 44 to receive the levers. The lever for the slide of the coin reservoir 50 is continued forward to form a key lever 45 (Fig. 5) provided with a finger button 46 by which it may be depressed. The key levers for the other ejecting slides are shown at 47, provided with finger buttons 48, and are separate from the levers 40 which they actuate and operate them by means of a suitable number of independent yokes 49. These yokes are pivoted by their forwardly extending arms on the rod 41 and are arranged between the rear arms 51 of the key levers 47 and the slide propelling levers 40, so that an arm 51 may push a yoke 49 upward, and the yoke may push upward one or more of the levers 40 and actuate corresponding ejecting slides to deliver the desired amount of change. The upper sides of the arms 51 are recessed so as to actuate certain yokes and not actuate others, and the under sides of the levers are recessed so as not to be actuated by certain yokes and be actuated by others, with a result that the key levers 47 have a selective operation as to

pushing forward the coin-ejecting slides. This part of the machine is constructed according to the construction and arrangement set forth in my pending application Serial No. 779,663, to which reference is hereby made for the details of form and arrangement of the said parts. Each of the buttons 46, 48, is marked with a number (Fig. 1) showing the total amount of change which the depression of its lever will cause to be ejected from the coin reservoirs, by the slide or slides 31 operated by such depression, and to pass down the chute 4 onto the shelf 41.

52 indicates lock levers (Fig. 4), one beneath each slide 31, pivoted at 53 to the under side of the plate 2¹ so that an upward projection 54 on its front arm will be encountered and held down by the bottom coin of a stack, the lever being so held in contact with the coin by its rear arm 55 which in such position bears against the under side of the plate 2¹ (Fig. 5). The arm 55 and the plate 2¹ are slotted at 56, 57, to allow of the oscillation of the lever end 39. 58 indicates slide-locking projections on the front arm of the lever 52, which are shorter than the projection 54 and normally have their points just below the top surface of the plate 2¹ so that the slide cannot catch thereon, when the coins, by engaging the projection 54, hold the front end of the lever down in normal position (Fig. 2). The arrangement is such that if there is a coin in each reservoir whose slide 31 is operatively connected with the key which may be touched, the said slides will all come forward and eject the complete amount of change indicated by the key. If however the coin reservoir of any such slide has no coin in it the lever 52 of such slide will assume the position shown in Fig. 7, by reason of the superior gravity of the rear arm 55 and the absence of a coin to hold down the projection 54, whereupon the front end of the slide will be engaged by the projections 58 and the slide will be locked, and so will the connected key lever if it be attempted to be depressed, and no coin will be ejected. This locking prevents the delivery of an incorrect amount of change, and signals that the coin in some reservoir is exhausted. 59 is a slot formed in the slide 31 to enable the slide to advance past the projection 54. 60 indicates a penny-changing attachment, which is more fully set forth in my said other application.

From the preceding description it will be seen that I have provided a coin change-making machine of relatively simple construction, composed of few parts and adapted to make change in any amounts varying from one cent to ninety-nine cents, and having also automatically operated means for preventing an incorrect amount of change being delivered which does not include pennies. Although I have herein shown and de-

scribed what I now consider the preferred embodiment of my improvements, yet it will be understood that various changes and modifications may be made in the details of construction and arrangement of parts without departing from the spirit of my invention, and all such changes and modifications are contemplated as fall within the scope of the claims appended hereto.

10 I claim:

1. In a change making machine, in combination: a frame having a fixed coin-supporting top plate formed with openings therein; coin ejecting slides mounted and operating on the said top plate; key mechanism for operating the said slides to eject coins; and coin reservoirs mounted above the said top plate and having coin supports 19 at the sides of each reservoir and extending 20 down through the openings in and independent of the top plate leaving a through passage for the slides from rear to front between the said coin supports and at the upper surface of the said top plate.

2. In a change making machine, in combination: a frame having a fixed coin-supporting top plate formed with openings therein; coin ejecting slides mounted and operating on the said top plate; key mechanism for operating the said slides to eject coins; and coin reservoirs mounted above the said top plate and having coin supports 19 at the sides of each reservoir and extending down through the openings in and independent of the top plate leaving a through passage for the slides from rear to front between the said coin supports and at the upper surface of the said top plate; the said coin reservoirs having a connecting and supporting frame which is removable from the rest of the machine, with the said supports.

3. In a change-making machine, in combination: coin reservoirs; mechanism for ejecting coins therefrom; keys connected with such mechanism for causing the same to eject various combinations of coins; and a coin carrier separable from the rest of the machine and having means for supporting the stacks of coin when the carrier is so separated, the said carrier being provided at each side with a spring-controlled latch, the rear end of which is upwardly movable to engage behind a shoulder of the frame of the machine, the said latch having a forwardly extending finger-piece forming a means for lifting the carrier, and the carrier being provided at each side with a thumb rest opposing said finger-piece and forming therewith a grip at each side of the carrier 60 for the simultaneous unlatching and lifting of the same.

4. In a change making machine, in combination: a top plate; coin reservoirs above said top plate; slides operable on the top plate to eject coins from the bottom of the

reservoirs and formed with longitudinal slots; and levers for locking the slides, which levers are provided with locking projections under the coins in the reservoirs and having pivots and rear weighted ends 70 under the slides and having at their front ends upstanding coin-depressed projections, the locking projections being arranged at the front edges of the slides to engage the same at the sides of said slots and assuming 75 locking positions when such coins are absent, the said coin-depressed projections being received in said slots when the slides are advanced.

5. In a change-making machine, in combination: coin reservoirs; mechanism for ejecting coins therefrom; keys connected with such mechanism for causing the same to eject various combinations of coins; a coin chute for receiving the combination of 80 coins, provided with a spring-controlled tilting bottom shelf; and a cam operated independently of the keys and at will for holding the said bottom shelf depressed 85 and open; substantially as specified.

6. In a change making machine, in combination: a top frame plate; coin reservoirs above said top plate; slides operable on the top plate to eject the coins from the bottoms of the reservoirs; and levers for locking the slides, which levers are provided with rearward locking projections upstanding at the sides of the levers and arranged at the front edges of the slides and which assume locking positions when such coins 90 are absent and coin depressed front projections 95 adapted to be engaged by the coins when present in the reservoirs to hold the locking projections from engagement with the slides.

7. In a change making machine, in combination: a frame; a fixed coin-supporting top plate arranged below and spaced from the top of the frame and formed with coin-escape openings, longitudinal slots and 110 openings 21; coin-ejecting slides mounted on said top plate in the space between the same and the frame and formed with lugs which fit in the longitudinal slots of the top plate and with slots in line with the said openings 21; key mechanism for operating the said slides to eject the coins; and coin reservoirs mounted on the said frame and having coin supports independent of the frame and top plate and arranged at the sides of 115 each reservoir and extending down through the frame and said openings 21, the said coin supports being received in slots of the slides when the latter are advanced.

8. In a change making machine, in combination: a casing; change-making mechanism therein; a coin reservoir on the front of the machine on the coins in which the said mechanism operates, said coin reservoir being removable from the casing; movable 120

latches mounted on the coin reservoir and engaging behind parts of the casing, one latch at each side of the reservoir, said latches being disengageable by lifting up on them; and finger levers on the reservoir whereby said latches are released by upward movement and the reservoir lifted.

Signed this 28th day of May, 1914, in the presence of two subscribing witnesses.

WILLIAM P. DUN LANY.
